UNITED STATES PATENT OFFICE.

BENTON WILSON, OF CAMBRIDGE CITY, INDIANA.

AUDITORIUM-SEAT.

937,131.

Specification of Letters Patent.

Patented Oct. 19, 1909.

Application filed January 21, 1909. Serial No. 473,600.

To all whom it may concern:

Be it known that I, BENTON WILSON, a citizen of the United States, residing in Cambridge City, in the county of Wayne 5 and State of Indiana, have invented certain new and useful Improvements in Auditorium-Seats, of which the following is a full, clear, and accurate specification, being such as will enable others to make and use the 10 same with exactitude.

The object of my invention, broadly speaking, is to provide seats for use in auditoriums or the like where the seats are to remain in a relatively fixed position and 15 arranged in rows, and at same time allowing the seats to be folded and unfolded independent of each other and allowing for a comparatively wide passage-way between the rows of seats.

20 In carrying out the principles of my invention in a practical manner I employ folding chairs similar to the chair shown in Letters Patent No. 583,342, and substantially as shown in the drawings forming a 25 part of this specification. Heretofore folding chairs of this character have only been used singly and allowed to be loose upon the floor for the reason that no practical means had been devised for securing the chairs to 30 the floor and at same time allowing them to be opened and closed, therefore to overcome this difficulty is the primal object of this present invention.

35 Other minor objects and particular advantages of my invention will present themselves in the course of the following description, and that which is new and useful will be correlated in the appended claims.

40 In order that my invention may be more fully understood reference is had to the accompanying drawings, in which,—

Figure 1 is a perspective view of a plurality of chairs equipped with my invention. Fig. 2 is an isometrical view of the brace, 45 which is the essential element of this invention. Fig. 3 is an end view showing the seat open or unfolded. Fig. 4 is the same as Fig. 3, except that the seat is shown closed or folded. Fig. 5 is a detail view showing one 50 of the shoes. Fig. 6 is a detail longitudinal section of the lower portion of the brace shown in Fig. 2. Fig. 7 is a perspective detail view of the rivet used to connect the two members of said brace. And Fig. 8 is a cross 55 section taken through the body portion of the rivet used in connection with the brace.

Similar indices denote like parts throughout the several views.

In connection with said drawings I will now take up a description of the invention 60 and will refer to the several parts as briefly and as comprehensively as I may.

In carrying out my invention I employ a plurality of folding chairs as for instance the chairs A, B and C, which are of a construction identical with each other, in which the standards for the back of the chair extend downward and forward forming the front feet *a*, *b* and *c*, respectively. The seats of the chairs are hinged to the back and are 70 adapted to be turned up parallel therewith. The upper ends of the cross legs are pivoted to the sides of the seat and then extend back and downward forming the rear feet *a'*, *b'* and *c'*, respectively. It will be evident that 75 my invention may be successfully employed with only one of such chairs, but I prefer to form the chairs in multiple, and for this purpose I connect each row of chairs by means of the two bars 1 and 2. The bar 1 is gained 80 in and secured by bolts to the rear edges of the back standards at a point slightly below the seat, and the bar 2 is likewise attached to the front edge of said standards at a point lower than the first bar, substantially as indicated in Fig. 1. It is apparent that any 85 number of chairs may be thus connected together, they being spaced the desired distance apart. The means for connecting the chairs, thus formed, to the floor, is substantially as follows: The numeral 3 denotes the 90 main member of the brace, the upper end portion of which is flattened laterally and bent at an angle forming the part *3^a* which is provided with bolt apertures as indicated 95 in Fig. 2 to provide means for its attachment to the rear face of the bar 1 as shown. The opposite end portion of the member 3 is flattened longitudinally forming the part *3^b* and this is provided with a slot *3^c* formed 100 longitudinally thereof. The member 4, of the brace, is of comparatively short length, but it is of same width as the member 3. Through one end portion of the member 4 is formed the screw aperture *4^a* and through 105 the opposite end portion is formed an aperture for the rivet 5, hereinafter referred to. The member 4 is bent near its center at an obtuse angle. Said rivet 5 is provided with a head of such size as not to pass through 110 the slot *3^c*, while the body thereof is adapted to slide in said slot, and the end opposite the

head is adapted to pass through said second named aperture in the member 4, projecting back and riveted down on the back of the member 4, as indicated in Fig. 6. That portion of the shank, of said rivet, which passes through the slot 3^e is formed square, or oblong in cross section thereby providing two parallel sides which may engage the sides of the slot 3^e to retain the member 4 in alignment with the member 3 yet free to move longitudinally and independently thereof.

Each of the front feet of the chairs should be provided with a shoe, as the shoe 6 shown in Fig. 5. These shoes are formed to correspond with and fit over the feet of the chairs, and having means whereby the shoes may be secured to the floor by screws or otherwise. The feet *a*, *b* and *c* are free to move in and out of said shoes, but in practice they will 20 at no time be removed therefrom.

In practice the chairs are arranged upon the floor as desired, the brace or braces are then attached to the bar 1, near the center of the two end chairs, if more than one brace 25 be used, and extend back and downward to the floor where they are secured by screws or the like inserted through the apertures 4^a. Each of the feet *a*, *b* and *c* is then incased by one of the shoes 6 which are also secured 30 to the floor, and this completes the attachment of the seats in position. It is evident that a single chair may be secured in like manner, or any number of chairs may be connected together similar to that shown in 35 Fig. 1.

From the above it is apparent that the seats may be folded or unfolded as desired, as the movements of the rivet 5 in the slots 3^e and the movements of the feet in the shoes 40 6 are such as to allow the required flexibility to insure the successful operations.

I have also found in practice that only one of said braces is really necessary for each 45 row of chairs, that is where the chairs are secured together substantially as shown in Fig. 1, in which instance the brace should be located midway of the row of chairs.

I desire that it be understood that various 50 changes may be made in the details of construction without departing from the spirit of my invention or sacrificing any of the advantages thereof.

Having now fully shown and described the best means for the construction of my invention to me known at this time, what I 55 claim and desire to secure by Letters Patent of the United States, is—

1. A folding chair having means for attachment to a floor, said means including a

rear extensible brace, and shoes for the front 60 feet of the chair, the feet being free to move in said shoes.

2. A brace for connecting folding chairs to a floor, said brace having means for its attachment to a chair, means for its attachment to a floor, and means whereby it may have a limited longitudinal movement after being secured in position.

3. Means for connecting folding chairs to a floor comprising a brace having a limited 70 longitudinal movement within itself, and shoes in which the front feet of the chair may operate.

4. A plurality of folding chairs, means for connecting the chairs together laterally, 75 braces at the rear for connecting the chairs to a floor, said braces being provided with means for allowing a limited longitudinal movement within themselves.

5. A plurality of folding chairs or the like, bars connecting the chairs together, braces extending downward and rearward to the floor from one of said bars, and means by which the braces may have a limited longitudinal movement after being secured 85 in position.

6. A plurality of folding chairs, bars connecting the chairs together, a brace extending downward and to the rear from one of said bars with means for securing it to a 90 floor, means whereby said brace may at all times have a limited longitudinal movement to vary its length, and means for retaining the front feet of the chairs in position.

7. A brace for connecting chairs to a floor, 95 said brace comprising two members slidably connected together for limited longitudinal movements with relation to each other, and means for retaining said members in alignment with each other.

8. A brace for connecting chairs to a floor, said brace comprising a main member having one end thereof adapted for attachment to a chair, a second member having one end thereof adapted for attachment to a floor, 105 means for slidably connecting the other ends of said members together whereby they may have a limited longitudinal movement with relation to each other, and means whereby said members are at all times retained in 110 alignment with each other.

In testimony whereof I have hereunto subscribed my name to this specification in the presence of two subscribing witnesses.

BENTON WILSON.
